UNITED STATES PATENT OFFICE.

HAROLD D. WATERHOUSE, OF QUINCY, MASSACHUSETTS, ASSIGNEE, BY MESNE ASSIGNMENTS, TO WALTER S. CRANE, JOSHUA CRANE, AND FRANK V. STONE, TRUSTEES.

IGNITION APPARATUS.

1,381,773.

Specification of Letters Patent. Patented June 14, 1921.

Application filed January 14, 1918. Serial No. 211,737.

To all whom it may concern:

Be it known that I, HAROLD D. WATERHOUSE, a citizen of the United States, and a resident of Wollaston, city of Quincy, county of Norfolk, and State of Massachusetts, have invented an Improvement in Ignition Apparatus, of which the following description, in connection with the accompanying drawings, is a specification, like 10 characters on the drawings representing like parts.

This invention relates to improvements in ignition apparatus for internal combustion engines, and more particularly, though not 15 exclusively, to an improved distributor.

In the drawings I have elected to show a preferred form of one embodiment of my invention as applied to a Ford motor car.

Figure 1 is an end elevation of a motor 20 supplied with a preferred form of distributor constituting one embodiment of my invention;

Fig. 2 is a horizontal section, partly in plan, through the distributor shown in 25 Fig. 1;

Fig. 3 is a vertical transverse section, partly in elevation, on the line 3-3 of Fig. 2;

Fig. 4 shows the interrelation of the disassembled parts, which are shown in assembled relation in Fig. 2; and

Fig. 5 is a diagram showing a preferred wiring system for use in connection with my invention.

The improved distributor is preferably, though not necessarily, applied directly to the cam shaft 6 of the car, in the same general position as that occupied by the commutator of the Ford car. The amount of 30 space between the time gear cover casting 7 and the fan 8 of the car is relatively slight, and the distributor must be of peculiarly compact construction to avoid interference with the fan, while providing a sufficiently 40 long bearing to be durable.

In the preferred form of my invention I have provided a sleeve 8' preferably secured to the shaft 6 by a pin 9, and carrying a distributor ring 10 mounted on any suitable 50 interposed non-conductive rotating element 11, which also carries the distributor sector 12 connected to the distributor ring 10 in any suitable way typified by the wire 13. The sleeve 8' is preferably extended to provide cam surfaces 14 and an extended bear-

ing surface 15 beyond the cam surface. The cam surfaces 14 may conveniently be formed by those portions of the cylindrical surface of the sleeve 8' left after cutting slots through the sleeve 8' corresponding to the 60 number of cylinders to be fired by the distributor. To provide an elongated support for the sleeve 8', and also to provide bottom portions for the cam surfaces 14, I may, and preferably do, counterbore the interior of 65 the sleeve 8' to provide sufficient room for an interiorly threaded sleeve 16, which may be and preferably is formed as a part of a chambered nut adapted to engage the threads on the end of the cam shaft 6. The 70 nut 16 preferably bottoms against a shoulder 17 of the sleeve 8', thereby pressing said sleeve firmly against the pin 9. The timing shaft 6, which is of course a "half time" 75 shaft, the sleeve 8', distributor ring 10, distributor sector 12, the cam portions 14 and the nut 16 are, therefore, all locked together for joint rotation.

I will now describe those portions of the distributor which do not rotate with the cam 80 shaft 6. The housing for the distributor may comprise a casing 18 of any suitable non-conductive material, and preferably carries an electric connection 19, herein shown as a screw having its end adjacent the distributor ring 10 for supplying current thereto, and a plurality of connections 20, 21, 22 and 23 for successively receiving the current from the distributor sector 12, those connections being respectively connected to the 85 spark plugs 24, 25, 26 and 27 of the internal combustion engine. The casing 18 is preferably attached to the casting 7 in any suitable way, and is preferably provided with a bearing sleeve 28 engaging the exterior surface of the sleeve 8' through a considerable portion of its length. The sleeve 28 is preferably slotted at 29 to receive the cam-engaging element 30, which is preferably carried by a breaker-arm spring 31 attached to 90 the breaker casing 32, which is preferably mounted for limited rotative movement about the sleeve 28. The cam-engaging element 30 controls the make and break of the primary circuit between the point 33 carried by the breaker-arm spring 31 and the stationary point 34. The breaker casing 32 is preferably provided with a removable cover 35 secured to the breaker casing by the screw 36 and the screw 37 which may, as shown, 105 110

support the breaker-arm spring 31. The stationary point 34 of the circuit breaker is preferably carried by the cover 35. To advance or retard the spark, the entire breaker casing and parts carried thereby may be oscillated about the sleeve 28. To hold the sleeve 28 and parts carried thereby in place on the sleeve 8'-15, I may provide a disk 38 adapted to be pressed against the end of the sleeve 28 by a spring 39 carried by any suitable stationary portion of the motor such as the "breather" pipe 40 on the time gear cover 7.

In Fig. 5 I have shown diagrammatically a preferred form of wiring system for use in connection with my invention in which 41 represents a generator, the wire 42 a primary wire from the generator leading through the switch 43, primary coil 44 and buzzer 45 to the stationary breaker point 34. From the stationary breaker point 34 the current passes to the movable breaker point 33 and thence through the breaker arm 31 in connection 46 to the motor (ground) and thence through the connection 47 to the generator 41. The secondary circuit may be assumed to start from the motor (ground) at 48, passing through the secondary wiring 49, and secondary coil 50 to the connection 19 (Fig. 2), from which the current jumps to the distributor ring 10, which is connected with the distributor sector 12, from which the secondary current again jumps successively to the points 20, 21, 23 and 22, connected to the spark plugs, of each of which one point is of course grounded on the engine, thus completing the circuit.

While I have shown and described a preferred form of one embodiment of my invention, it will be understood that major changes involving omission, substitution, alteration and reversal of parts, and even changes in the mode of operation, may be made without departing from the scope of my invention, which is best defined in the following claims.

Claims—

1. In an internal combustion engine having a valve shaft, a nut, distributing means including a sleeve secured to the end of the valve shaft and counterbored interiorly to receive said nut engaging the threads on the end of said valve shaft, a second sleeve surrounding said first-named sleeve and removable therefrom over said nut while the latter remains in threaded relation to the shaft.

2. In an internal combustion engine having a valve shaft, a sleeve surrounding the end of the valve shaft and carrying a distributor ring and distributor sector, said sleeve being slotted completely through in places to provide a plurality of cam surfaces.

3. In an internal combustion engine having a valve shaft, a sleeve surrounding the end of the valve shaft and carrying a dis-

tributer ring and distributor sector, said sleeve being slotted to provide cam surfaces and being counterbored interiorly to receive a nut providing a supporting surface for said sleeve beyond the end of said valve shaft. 70

4. In an internal combustion engine having a valve shaft, distributing means comprising a sleeve secured to the end of the valve shaft and a cam rotatable with said valve shaft, a non-rotating sleeve surrounding the first-named sleeve carried thereby and having an extended bearing on the surface thereof and circuit making and breaking means carried by said second sleeve and mounted for limited movement thereon for advancement or retardation of the ignition. 75

5. In an internal combustion engine, a distributing device comprising, in combination, a sleeve for engagement with the end of a half-time shaft, said sleeve having slots 85 providing cam surfaces, a second sleeve surrounding the first-named sleeve, and carrying means coöperating with said cam surfaces for making and breaking the circuit.

6. In an internal combustion engine, a distributing device comprising, in combination, a sleeve for engagement with the end of a half-time shaft, said sleeve having slots providing cam surfaces and presenting an annular exterior bearing surface on both 95 sides of said slots, a second sleeve surrounding the first-named sleeve, and carrying means coöperating with said cam surfaces for making and breaking the circuit. 90

7. In an internal combustion engine, a distributing device comprising a cam carried by a half-time shaft, a coöperating make and break member, a breaker casing for said make and break member and a removable cover carrying a coöperating point 105 for said make and break member, said cover being removable from said casing without disturbing the relation of said breaker and its cam.

8. In an internal combustion engine, the combination of a half-time shaft having a projecting end, and distributing means comprising a sleeve and a cam carried by and rotatable with said end of said shaft, a distributor ring and sector carried by said 115 shaft, a non-rotating sleeve, a coöperating casing 18 carried by said non-rotating sleeve, the latter having an extended bearing engagement with said sleeve rotatable with said shaft, and resilient means for holding 120 said casing and coöperating non-rotative parts in assembled relation with said shaft and coöperating rotating parts.

9. In an internal combustion engine, a distributing device comprising a shaft, a nut 125 threaded to the end of said shaft and providing a round exterior portion, a sleeve secured to said shaft and extending over said nut, slots in said sleeve, said sleeve and said nut providing a plurality of cam surfaces, and a 130

make and break device actuated by said cam surfaces.

10. In an internal combustion engine, a distributor device comprising a rotary shaft, 5 a distributor cam fixed relative to said shaft and rotatable therewith, a distributor casing said shaft extending through both ends of said casing, a breaker point and means for moving said breaker point to advance or 10 retard the spark while leaving said dis-

tributer casing stationary, said breaker point being located adjacent the outer end of said shaft, an end thrust disk arranged at the end of said shaft and resilient means to detachably secure said disk in position to retain 15 said breaker point in operative relation to said shaft.

In testimony whereof, I have signed my name to this specification.

HAROLD D. WATERHOUSE.
